UNITED STATES PATENT OFFICE.

GEORGE F. HIGGINS, OF MELROSE, MASSACHUSETTS.

COIN-CONTROLLED APPARATUS.

Application filed November 25, 1921. Serial No. 517,499.

This invention relates to a coin-controlled apparatus and has for one of its objects to provide a novel apparatus involving a plurality of devices to be independently actuated, and a common actuator for actuating the devices selectively by the insertion of coins in different coin slots. The construction is such that normally the common actuator is inoperative to actuate any of the devices but it becomes operative to actuate any device when a coin is inserted in the slot corresponding to said device, there being a coin slot for each of the devices to be actuated.

The invention is capable of a wide variety of uses and is particularly useful when embodied in a vending machine as in such case it may be used in connection with a vending machine arranged to vend a plurality of different articles. In such case there will be a coin slot for each article to be vended and a single actuator for effecting a release of anyone of the articles dependant on the slot or slots in which the coins have been inserted. One convenient way of arranging a device embodying the invention is in the form of a cabinet having a plurality of compartments each adapted to contain an article to be vended and each having an opening through which the article is delivered and which is closed by a door or closure. Each door has its own lock for locking it closed and the common actuator, which is normally inoperative to release any of the locks, will become operative to release any lock by the insertion of a coin in the slot corresponding to said lock.

Another feature of the invention relates to means by which a properly authorized person may release all of the doors or closures simultaneously whenever it is desired to get access to the various compartments for refilling them or for other purposes.

In order to give an understanding of the invention I have illustrated in the drawings some selected embodiments thereof which will now be described after which the novel features will be pointed out in the appended claims.

Fig. 1 is a front view of a device embodying my invention.

Fig. 2 is an enlarged sectional view on the line 2—2, Fig. 3.

Fig. 3 is a section on the line 3—3, Fig. 2.

Fig. 4 is a view showing a different embodiment of the invention.

Fig. 5 is an enlarged transverse sectional view.

Fig. 6 is a view of a door arranged to swing in either direction.

In its broad aspect my invention comprehends a plurality of devices to be actuated, a common actuator by which each of the devices may be operated, and an arrangement whereby the actuator is normally inoperative but becomes operative to selectively actuate the devices by inserting coins in various coin slots, there being one coin slot for each device to be actuated.

As stated above while the invention is capable of a wide variety of uses I regard it of especial advantage when used in connection with a vending machine and when used in this way I propose to provide a vending machine having a plurality of compartments each adapted to hold some article to be vended, and to provide each compartment with an opening through which the article may be delivered, a closure for the opening, and a lock to lock the closure closed. Each compartment has associated therewith a coin slot and the arrangement is such that when a coin is deposited in any slot and the common actuator is operated, the coin forms an operative connection between the actuator and the lock of the compartment corresponding to the coin slot which has received the coin so that when the actuator is operated the lock for this compartment will be released.

There is normally no operative connection between the actuator and each lock so that unless a coin has been deposited in any slot the operation of the actuator will have no effect upon the lock.

In the drawings I have shown at 1 a cabinet having a plurality of compartments 2 each having an open front that is closed by a closure or door 3. The compartments are herein shown as arranged in two pairs thus making two vertical tiers of doors or closures 3. Each door is pivoted at its outer edge as shown at 4. If desired each door may have a sight opening 5 therein which is closed by suitable transparent material so that the customer may see the character of the articles in each compartment. Associated with each compartment is a coin slot indicated at 6 and for the reception of a coin of proper denomination.

Each door is normally locked by a suitable locking device and in the construction

herein shown the lock for each door comprises an arm 7 extending from the inner face of the door and a pivoted spring-pressed member 8 normally engaging the arm.

5 A single actuator is employed common to all the latches, but which is normally disconnected from the latches so that the operation of the actuator will not release any of the latches. Means are provided whereby when a coin is deposited in any one of the slots 6, then such coin will form an operative connection between the actuator and the corresponding latch so that when the actuator is operated the latch will be released thereby to open the corresponding door. The movement of the actuator, however, has no effect upon the other latches, so that the latches may be selectively released by this actuator merely by dropping coins in selected slots. The coin slots 6 for each vertical tier of doors open into a vertical passage-way or chute 9 formed between two vertically-extending plates 10 that are secured to the front of the cabinet and are spaced apart a proper distance to receive the coin. There are two such passages or chutes 9, one for each vertical row of coin slots and both passages open at their lower end into a coin-receiving drawer 11. Each latch 8 is pivotally connected to the upright plates 10 as shown at 12 and the rear end of each latch is formed with a tail portion 13 which is bent back parallel with the body of the latch and extends into the space between the plates 10. This portion 13 of each latch is provided with a bevelled face 14 and when the latch is in normal position said bevelled face is so positioned that there is insufficient space between the point thereof and the front of the cabinet to permit the coin to pass so that when a coin 15 is dropped into the chute 9 through a slot 6 it will be retained on the bevelled surface 14 as shown in Fig. 3. Each latch is acted upon by a spring 17 which yieldingly holds it in its operative position.

The actuator which is common to all the latches for releasing them is herein shown as a rod 18 situated within the housing and extending vertically, said rod being preferably placed between the two pairs of upright plates 10. This rod is provided with a handle or projection 19 extending through a slot 20 in the front of the cabinet and by which the rod may be depressed. The rod also is provided with latch-releasing extensions 21, there being one such extension for each coin slot, said extensions extending through slots in the inner plate 10 and the ends of the extensions operating in the spaces 9. Each extension 21 is so placed that it is normally situated above the coin slot 6 and is in a position to engage any coin which has been deposited in said slot when the actuator is moved downwardly. These

extensions 21 are also so positioned in front of the portions 13 of the latches so that when there are no coins in any passageways or chutes 9 the downward movement of the extensions does not operate any of the latches. The actuator is returned to its normal position by a return spring 43.

If, however, a coin has been deposited in any slot as shown in Fig. 3, then when the actuator is moved downwardly the corresponding extension 21 will engage the coin and will operate through the coin to produce a downward pressure on the bevelled edge 14 of the tail 13 of the latch thereby swinging the latch downwardly and releasing it from the arm 7. This will unlock the door and provide access to the compartment. It will be understood that some usual spring device will be employed to open each closure as it is released as is common in devices of this nature.

It will, therefore, be seen that I have provided a common actuator for releasing all the latches and have also provided an arrangement whereby the actuator is inoperative to release any latch until a coin has been inserted in a selected slot, at which time the actuator becomes operative to release the corresponding latch without, however, being operative to release any of the other latches. With my device, therefore, the latches can be selectively released from the common actuator by merely selecting the slot into which the coins are to be deposited.

I have also provided means whereby an authorized person may release all the latches simultaneously and thereby gain access to all compartments whenever it is desired to refill the same.

In Figs. 3 and 5 this is accomplished by a member 22 in the form of a vertically-extending rod situated in the rear of the actuator 18 and provided with arms 23 that extend underneath the rear ends 24 of the latches. When the releasing rod 22 is raised the arms 23 will operate all of the latches and thereby release them all. This releasing member 22 is normally inaccessible but access to it can be obtained through the opening in which the money drawer 11 is received. This money drawer which receives the coins from the chutes is normally locked but can be opened by any authorized person, and when the drawer is removed then the operator may insert his finger in the opening and press upwardly a pivotal plate 42 that bears against the lower end of the rod 22 thereby to effect the release of the latches.

I may, if desired, utilize the actuator 18 for this purpose of releasing all the latches simultaneously. This can be done by providing said actuator with rearwardly-extending arms 25, the ends of which are situated beneath the outer ends 24 of the latches.

In this case the actuator will be moved downwardly from its neutral position to selectively release any latch and will be moved upwardly from this position to release all the latches simultaneously. To prevent an unauthorized person from thus releasing all the latches simultaneously I propose to employ a guard plate 26 which normally prevents the finger piece 19 from being raised beyond the neutral position while permitting it to be moved downwardly freely. This guard plate can be locked in its operative position and when unlocked it may be swung aside to permit the finger piece 19 to be raised.

If desired, I may make each closure with its arm 7 so positioned that the closure may be used either on the right hand side or the left hand side of the device, the change from one side to the other involving merely reversing the door.

In the above description and in the claims I have used the term "coin" as referring to the article 15 which is used to make an operative connection between the actuator and the latch. I have used this term, however, in a generic sense and intend it to cover not only coins such as are used for money but also any specially made coin or check which is designed for use in slot machines.

I claim.

1. In a coin-controlled apparatus, the combination with a plurality of compartments each having an opening, of a closure for each opening, a coin chute, coin slots, one for each closure opening into said chute, a pivoted U-shaped member for each opening, one arm of each member constituting a locking latch for the corresponding closure and the other arm extending into the coin chute, each closure having a latch-engaging part with which the latch engages, a single actuating member constructed to act against any coin deposited in a slot and resting against one arm of one of said U-shaped members thereby to operate through said coin to release the corresponding latch.

2. In an apparatus of the class described, the combination with a plurality of compartments, one above the other, each being open at the front, of a closure for each opening, two parallel plates extending at right angles to the plane of the closure and forming between them a coin chute, a plurality of coin slots, one for each closure leading to the

chute, a pivoted latch for locking each closure, latch-engaging means for each latch, each latch having an extension between the plates and in the path of a coin deposited in the corresponding slot, whereby such a coin 60 when deposited will be supported on the extension, and an actuator having a plurality of arms, one for each coin slot, each arm being situated above its coin slot, whereby when the actuator is moved a coin in any slot 65 will be engaged by one of the arms and will become operative to release the corresponding latch.

3. In an apparatus of the class described, the combination with a plurality of compartments one above the other and each having an open front, of a closure for each opening having latch-engaging means, a plate parallel with a side wall of the compartment and forming therewith a coin 75 chute, a plurality of coin slots leading to the chute, a latch for each closure, each latch being pivoted to the wall of the compartment and situated within the compartment, each latch also having an extension situated 80 exterior to said side wall and between the latter and said plate and normally occupying the path of a coin deposited in the corresponding coin slot, and a reciprocating actuator constructed to act against a coin 85 deposited in any slot thereby to release the corresponding latch.

4. In an apparatus of the class described, the combination with a plurality of compartments one above the other and each having an open 90 front, of a closure for each opening having latch-engaging means, a plate parallel with a side wall of the compartment and forming therewith a coin chute, a plurality of coin slots leading to said chute, a latch for each 95 closure, each latch being pivoted to the wall of the compartment and situated within the compartment, each latch also having an extension situated between said plate and the compartment wall and normally occupying 100 the path of a coin deposited in the corresponding coin slot, a reciprocating actuator constructed to act against a coin deposited in any slot thereby to release the corresponding latch, and other means to release 105 all the latches simultaneously.

In testimony whereof, I have signed my name to this specification.

GEORGE F. HIGGINS.
